(57) **CLAIM**

The ornamental design for an electric stun gun, as shown.

DESCRIPTION

FIG. 1 is a front isometric view of the electric stun gun of the present invention;

FIG. 2 is a rear isometric view of the invention;

FIG. 3 is a side view of the invention of FIG. 1, as seen from the right side of FIG. 7;

FIG. 4 is a side view of the invention of FIG. 1, as seen from the left side of FIG. 7;

FIG. 5 is a top plan view in elevation of the invention of FIG. 1;

FIG. 6 is a bottom plan view of the invention of FIG. 1;

FIG. 7 is a front view of the invention of FIG. 1; and,

FIG. 8 is a rear view of the invention of FIG. 1.

The broken lines show various buttons and interface mechanisms and form no part of the claimed design.
